CLAIM

The ornamental design for a micro power connector, as shown and described.

DESCRIPTION

FIG. 1 is a top, front and right side perspective view of a micro power connector, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view.

The broken lines shown in the drawing views represents unclaimed environmental portions only and form no part of the claimed design.
